D5-27

EX

D5379

OR D 16,593

DESIGN.

—o—
S. LOEWENHERZ.

ORNAMENTATION OF LEATHER, &c.

No ~~D~~ 16,593.

Patented Mar. 30, 1886.

UNITED STATES PATENT OFFICE.

SIGMUND LOEWENHERZ, OF NEW YORK, N. Y.

DESIGN FOR THE ORNAMENTATION OF LEATHER, &c.

SPECIFICATION forming part of Design No. 16,593, dated March 30, 1886.

Application filed February 13, 1886. Serial No. 191,902. Term of patent 3½ years.

To all whom it may concern:

Be it known that I, SIGMUND LOEWENHERZ, a citizen of the United States, residing at New York, in the county and State of New York, have invented and produced a new and original Design for Ornamenting Leather and other Fabrics, of which the following is a specification, reference being had to the accompanying drawing, forming part thereof.

My invention consists in a new and original design for ornamenting leather and other fabrics, such as are used in the manufacture of satchels and the like, the said invention being fully pointed out in the following specification and claim and illustrated in the accompanying drawing.

In the upper left-hand corner of the drawing is represented a Chinese or Japanese group, A, consisting of an individual drawing a vehicle upon which is seated a person, while in the rear are following a number of attendants in various attitudes. Below this representation is pictured a stream, B, the high and abrupt banks of which are spanned by a pole of bamboo, and making their way across the latter are two acrobats, one on his feet fanning himself, while the other is crossing the pole on his hands. A group of individuals on one of the banks of the stream are intently gazing at the performers. Two vessels, one sailing from and the other toward the observer, are shown. Below this latter are pictured a Chinese lady, C, and children, and below this representation, and somewhat to the right, a party is shown about to disembark from a boat, D. Two of the persons, who carry flags, are shown in the act of stepping ashore, and are apparently in conversation with a Chinese lady seated on the bank, while the remainder are still seated in the boat. The banks of the river are studded with a vegetation of a reedy growth. Beneath this elevation the river is arched over and passes through a mountainous region. Vessels are shown sailing in opposite directions on the river. In the extreme lower left-hand corner is pictured a Chinese or Japanese dwelling-house, E, which is surrounded by foliage, and in front of the house is a pillar bearing a Chinese inscription.

In the upper central portion of the drawing is represented a broad river, F, spanned by an arched bridge, and moving in the direction of the observer is a vessel bearing a large number of persons, part of which number are standing upright in the bow of the boat. Beneath this landscape are shown Japanese athletes, F', engaged in an exciting wrestling contest, and below this is pictured a water-carrier, F'', attired in a fantastic costume, and to his left is a well, from which he has just filled his buckets, which he carries suspended from either end of a slender rod. In the upper right-hand corner is represented part of a Chinese dwelling, G, the occupants of which are seated in various postures in front of a screen bearing Chinese inscriptions and portraits. Below this is shown a Chinese archer, H, apparently supported upon a flock of birds, and to his left are fencers engaged in a contest. In the lower right-hand corner is represented a scene in which mounted travelers, I, are pursued by wolves, and the travelers are shown in the act of drawing their bows.

The herein-described main features of the design are interspersed with other representations of more or less importance in enhancing the attractive appearance of the design, of which may be mentioned a bird, a, near the lower left-hand corner, and a beetle, b, to the left of the bird. Near the upper right-hand corner a Chinaman, c, is shown seated and engaged in writing, and below the latter is a second individual, d, apparently engaged in vigorously expounding some doctrine, and to his left are fierce-looking warriors, e e'. Farther downward is a Chinese lad, f, with his hands to his face, as if frightened by the approaching insect. Below this are shown a pair of Chinamen, f', engaged in conversation and smoking their pipes.

What I claim as new, and desire to secure by Letters Patent, is—

The design herein described and shown for the ornamentation of leather and other fabrics, consisting in the representation in relief of a river flowing through a landscape, of a boat, D, floating thereon, of persons in the act of disembarking from said boat, persons in said boat, and the figure of a woman upon the bank, the whole being substantially as shown and described.

In testimony whereof I have hereunto set my hand and seal in the presence of two subscribing witnesses.

SIGMUND LOEWENHERZ. [L. S.]

Witnesses:

S. VAN ZANDT,
A. FABER DU FAUR, Jr.